CLAIM

The ornamental design for an exterior address porch light with cylindrical body with address window, cap cover, and bottom end cover with holes, as shown and described.

DESCRIPTION

FIG. 1 is an upper front right perspective view of an exterior address porch light with cylindrical body with address window, cap cover, and bottom end cover with holes.

FIG. 2 is an lower front left perspective view of the exterior address porch light of FIG. 1.

FIG. 3 is a front side view of the exterior address porch light of FIG. 1.

FIG. 4 is a right side view of the exterior address porch light of FIG. 1.

FIG. 5 is a left side view of the exterior address porch light of FIG. 1.

FIG. 6 is a rear side view of the exterior address porch light of FIG. 1.

FIG. 7 is a top view of the exterior address porch light of FIG. 1; and,

FIG. 8 is a bottom view of the exterior address porch light of FIG. 1.

The broken lines showing of side mounting plate, solar panel on top, and numbering across the front window in FIGS. 1–8 are for illustrative purposes and form no part of the claimed design.
